(57) **CLAIM**

The ornamental design for stylus, as shown and described.

DESCRIPTION

FIG. 1 is a perspective view according to a first embodiment our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is another perspective view according to our new design and the broken lines showing an electronic device is ready to be supported by the stylus; and,

FIG. 9 is another perspective view according to our new design and the broken lines showing an electronic device is ready to be touched by the stylus.

The broken lines shown in figures illustrate environmental structures and form no part of the claimed design.
